UNITED STATES PATENT OFFICE.

CHRISTIAN WRAYGE, JR., OF CASS LAKE, MINNESOTA.

DISPLAY CONTAINER AND STAND.

1,113,725.

Specification of Letters Patent. Patented Oct. 13, 1914.

Application filed September 24, 1913. Serial No. 791,483.

To all whom it may concern:

Be it known that I, CHRISTIAN WRAYGE, Jr., citizen of the United States, residing at Cass Lake, in the county of Cass and State 5 of Minnesota, have invented certain new and useful Improvements in Display Containers and Stands, of which the following is a specification.

This invention relates to a stand and container especially adapted for handling, displaying and protecting bananas or other food products which, for sanitary reasons, should be protected from flies and from improper handling.

15 One of the important objects of my invention is to provide a stand in which the food products may be easily placed therein and readily removed therefrom either in bulk or in detached portions.

20 A further object is to provide a device of the character stated that may be readily disassembled for shipment or packing.

A further object is to provide means whereby any flies entering the container may 25 escape therefrom.

Further objects of general utility are conserved by my invention as will be readily apparent to those skilled in the art to which it relates.

30 Referring to the accompanying drawing, which forms a part of this application I have illustrated my invention in preferred form in the following views:—

Figure 1 shows in elevation a container 35 and stand constructed according to my invention; Fig. 2 is an enlarged sectional detail of the top of the container showing the manner in which it is suspended, and Fig. 3 is an enlarged detail in elevation of the 40 top plate or collar.

Referring to the details of the drawing, the reference characters 4, 4^a, represent respectively the two semi-cylindric sections which form the main body of my improved 45 container and are preferably formed of wire gauze or fabric though other forms of reticulated metal or material may be used if desired. The edges of these sections are bound and reinforced by thin metal straps 50 5 and 6, the latter being applied to the vertical edges and the former to the horizontal edges, and are bent to conform to the cylindric contour of the sections 4, 4^a. The top 55 of the container is composed of two half cones 4^b the bases of which are secured to

their respective halves of the cylinder or body 4, 4^a, by the metal bands 5. The bottom 4^c of the container is formed in substantially the same manner as the top and both the top and bottom are made from the same material as the sides or body of the container. The section 4 has doorways provided therein, the edges of which are reinforced by the metal straps 5 and 6, and at the hinged side of said doorways are provided hinges 4^d by which the vertical edges of the sections are connected, corresponding hinges (not shown) being used along the opposite edges of said sections. These doorways are provided with doors 20, 21, which are hingedly connected with one of the edges of the section 4 by hinges 20^a, 21^a, respectively. These doors are also provided with hooks 22 pivoted on the door and adapted to engage pins 23 on the adjacent portion of the door frame. The two doors, as provided, are practically co-extensive in length with the vertical side of the sections 4, 4^a, and are of sufficient width to provide for the insertion and removal of bulky commodities, such as a bunch of bananas, or if the container is made sufficiently large for more than a single bunch of bananas.

The apex of the cone formed by the top sections 4^b is reinforced by a collar 7, composed of the conical sections 7^a, 7^b, which are preferably made of sheet metal and riveted to the wire fabric by rivets 4^e, as shown in Fig. 2. These half conical plates are connected at their meeting edges by hooks 12, pivoted on one of the plates and detachably engaging pins 13 on the corresponding plate, as shown in Fig. 3. The plates, at their upper edges, are bent inwardly to form a collar 7^c.

At the bottom of the container the plates 8, similar to the plates 7^a, 7^b, are arranged and terminate at their lower edges in a point 8^c adapted to fit in a corresponding recess formed in the top of the base 9 of the supporting stand. The stand, in addition to the base 9, is made up of a tubular standard 10, bent at its upper end to form a horizontal arm 10^a, and reinforced by angular braces 10^b. Near the outer end of the arm 10^a a vertical opening is provided for the upper portion of a bolt 11 the lower end of which is provided with a hook 11^a. The shank of the bolt is threaded as at 11^b and carries thereon nuts 14, 17, and 18. Between the 110

ends 14 and 17 are arranged circular plates 15, 16, which engage the collar 7^c and form a wide bearing for the top of the container. The opening through the pipe arm 10^a is 5 sufficiently large and is non-threaded so that the bolt 11 will turn freely therein. The nut 18 at the outer end of the bolt carries so much of the weight of the container and the bananas arranged therein as is not cared for 10 by the bottom bearing 8, 8^a. At intervals in the sides and top of the container I place small cones 19 of wire gauze in the apex of which are openings through which flies that enter the container when the doors are open 15 may escape.

It is obvious that in the construction of the device shown and described various details such as ball bearings and strengthening bands or other means may be provided 20 all within the scope of my invention, the same not being shown as they are well known mechanical expedients.

What I claim as my invention is:--

1. A container consisting of semi-cylindric sections of reticulated material, having 25 doorways provided therein, doors mounted in said doorways, conical top and bottom sections for said container, means for detachably connecting said sections, and means for supporting said container. 30

2. A container consisting of two cylindric sections, and conical top and bottom sections, said sections being detachably connected, doors for said cylindric sections, means for rotatably supporting said containers, said means connected with the conical sections, and means for supporting articles within said container. 35

In testimony whereof I affix my signature in the presence of two witnesses.

CHRISTIAN WRAYGE, JR.
